UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

SHOE.

1,191,535.

Specification of Letters Patent. Patented July 18, 1916.

Original application filed May 21, 1913, Serial No. 768,974. Divided and this application filed September 15, 1914. Serial No. 861,821.

To all whom it may concern:

Be it known that I, ADAM H. PRENZEL, a citizen of the United States, residing at Halifax, in the county of Dauphin and State of Pennsylvania, have invented certain Improvements in Shoes, of which the following description, in connection with the accompanying drawings, is a specification, like reference characters on the drawings 10 indicating like parts in the several figures.

This invention relates to shoes and has for its general object to improve the construction of stitch-down shoes.

Stitch-down shoes, as they have been manufactured up to the present time, may be classified generally as single sole stitch-downs, which cannot be repaired without relasting, and double sole stitch-downs, which have the upper secured to an insole as well 15 as to an outsole and which can therefore be repaired, so far as replacing the outsole is concerned, without relasting. In the manufacture of both kinds of stitch-down shoes, little attention has been paid to the support 20 of the upper upon the inside of the shoe and to the proper shaping of the shoe with the result that stitch-down shoes are generally in disfavor.

An object of the present invention is to 30 improve the construction of the stitch-down shoe that without increasing materially the cost of the shoe, both its appearance, its fit and its wearing qualities may be improved.

A further object of the invention is to 35 produce a stitch-down shoe which can easily be repaired.

A particular object of the invention is the production of a stitch-down shoe which is especially adapted to be manufactured by 40 the staple lasting process and which, when so manufactured, has substantially every appearance and substantially all the qualities of the best grades of shoes.

A preferred method of making the shoe 45 constituting the present invention is disclosed and fully described in my co-pending application Serial No. 768,974, filed May 21, 1913, of which the present application is a division.

50 Other objects and important features of the invention will appear from the following description and claims when considered

in connection with the accompanying drawings, in which—

Figure 1 is a perspective view, partly in section, showing the construction of, and the mode of preparing, the insole employed in the manufacture of the shoe of this invention; Fig. 2, by section and elevation, shows the manner of lasting the shoe and of securing the insole to the upper; Fig. 3 shows, in broken perspective, a completed shoe and, in section, the relative positions of the different parts of the shoe; and Fig. 4 illustrates an alternative mode of preparing the insole.

In order that the shoe may be resoled without lasting, it is essential that the upper be secured to an insole independently of its connection with the outsole. It is important also, in order that the upper may keep its shape as it is worn, that there be provided upon the inside of the upper some support above the point or line where the upper is bent outwardly to form the out-turned flange by which it is secured to the insole and outsole.

To provide an insole to which the upper may be secured independently of its attachment to the outsole and at the same time 80 to provide means for supporting the upper upon the inside and furthermore to provide a shoulder or a crease against which or into which the upper may be forced in the lasting operation is one of the objects of the invention, the invention aiming particularly 85 to provide these elements without increasing materially either the material cost or the labor cost of manufacturing the shoe.

In Fig. 1 is shown the insole provided 90 with the upper supporting means, this insole being preferably formed, as shown in Fig. 1, by providing the usual so-called "extension insole" 2, that is, an insole which will extend to the edge of the outsole, and securing to this extension insole an insole proper 95 4 which will be of such dimensions and outline that it will substantially fit the bottom face of the last and will lie inside the upper and furnish a shoulder or inside support 6 for the upper.

In order to provide proper insulation of the foot from the ground and also to cushion the foot, a filling piece 8 of felt, felt paper

or other suitable material is preferably interposed between the insole proper 4 and the extension insole 2, this piece, as shown in Figs. 1, 2 and 3, being located inside of 5 the stitches 10 by which the insole 4 has been secured to the extension insole 2, although it will be obvious that this piece can extend, if desired, out far enough so that the stitches 10 will pass through it and so 10 that it will tend to separate the two insole parts to open the crease to facilitate the lasting operation. This alternative construction is shown in Fig. 4.

It will be noted that the stitches 10 secure the insole proper 4 to the extension insole 2 only in the shank and throughout the forepart. At the heel end the insole 4 is preferably left unattached to the extension insole 2 to furnish a tongue 12 over 20 which the heel end of the upper and the counter may be turned in and lasted down, the lasting tacks being driven through and clenched upon the upper face of the tongue 12. At the point where the inturned and 25 outturned portions of the upper meet, the upper is preferably slit in from its edge in a well-known manner.

The insole, having been prepared in the manner shown in Fig. 1, is placed upon the 30 bottom face of the last so that the edges of the insole proper 4 are substantially flush with the edges of the bottom face of the last, the upper is placed upon the last and is then drawn over the edge of the last, and forced 35 into the crease between the edge of the insole proper 4 and the upper face of the extension insole 2, and is preferably secured to the extension insole 2 by staples 14 driven into the angle of the upper and through the insole 2 and clenched upon the bottom face of 40 said insole 2. This operation may conveniently be performed upon a lasting machine of the type shown in my co-pending application Serial No. 736,079 filed December 11, 1912, upon which United States Letters Patent No. 1,117,440 were granted November 17, 1914.

The shoe having been lasted in the manner just described and as shown in Fig. 2, 50 an outsole 13 is placed upon the bottom face of the extension insole 2, the welt 16 is laid upon the outturned flange of the upper, and the welt, upper, extension edge of the extension insole 2 and the outsole are united 55 by stitches 18. The welt 16 and the stitches 18 extend preferably from a point just beyond where the heel end of the upper is lasted, in upon one side of the shoe to a similar point upon the other side of the shoe. 60 The heel 20 is then placed upon the heel end of the shoe. The heel end 22 of the extension insole, the heel end of the outsole 13 and the heel are all united by nails driven through these parts and also through the 65 tongue 12 and clenched upon the inside of

the shoe. If desired the heel-seat may be nailed, independently of the nails which secure the heel, before the heel is placed upon the shoe.

From the foregoing description and from 70 the drawings it will be apparent that this shoe may be made with comparatively little labor, that the formation of the insole does not require the use of expensive materials to obtain the most satisfactory results, that 75 all of the operations in the manufacture of the shoe can be performed by the use of machinery, that the parts of the shoe are so confined inside and out that the shoe does not tend readily to lose its shape as it is 80 worn, and that when the outsole is worn through the shoe can easily be repaired since the upper is secured firmly and independently in its lasted position to the insole.

Having described my invention, what I 85 claim as new and desire to secure by Letters Patent of the United States is:—

1. A shoe comprising an upper, an insole proper located inside the upper, an extension insole secured to said insole proper and 90 upon the projecting edge of which the upper is outturned, the edge portion of said insole proper being unattached to the extension insole and the upper having its angle located in the angle between the lower marginal face of the insole proper and the upper face of the extension insole, means 95 attaching the upper permanently to said extension insole in said angle, and an outsole secured to said extension insole and said 100 upper.

2. A shoe comprising an upper, an insole proper located inside the upper, an extension insole upon the projecting edge of which said upper is outturned, a filling piece 105 between said insole proper and said extension insole, means for securing together said insole proper, filling piece and extension insole, means for securing said upper permanently to said extension insole, an outsole, 110 and means for securing said outsole to said extension insole and said upper.

3. A shoe comprising an upper, an insole proper, an extension insole and means for securing said insole proper to said extension 115 insole at a short distance from the edge of said insole proper, said upper being outturned and having its angle located between the lower marginal face of the insole proper and the upper face of the extension insole, 120 means for permanently securing the upper to the extension insole, located in said angle, a welt laid upon the upper flange and having its inner edge located in said angle, an outsole, and means for securing together said 125 welt, upper, extension insole and outsole.

4. A shoe comprising an upper, an insole proper located inside the upper, an extension insole upon the projecting edge of which the upper is outturned, means for se- 130

turing together the insole proper and extension insole at a distance from the edge of the insole proper, the angle between the upper and its outturned flange being located 5 between the lower marginal face of the insole proper and the upper face of the extension insole, staples securing the upper permanently to the extension insole located in said angle and clenched upon the bottom 10 face of said insole, an outsole, a welt lo-

cated upon the upper flange, and means for securing together the outsole, extension insole, upper and welt.

In testimony whereof I have signed my name to this specification in the presence of 11 two subscribing witnesses.

ADAM H. PRENZEL.
